United States Patent Office.

WILLIAM A. BURKE, OF LOWELL, MASSACHUSETTS, ASSIGNOR TO "THE PROPRIETORS OF THE TREMONT MILLS."

Design No. 4,156, dated June 21, 1870.

DESIGN FOR A TRADE-MARK.

The Schedule referred to in these Letters Patent and making part of the same

I, WILLIAM A. BURKE, of Lowell, in the county of Middlesex, and Commonwealth of Massachusetts, have invented and produced a new and original Design for a Trade-Mark, to be stamped or printed upon cloth to be manufactured by the aforesaid, "The Proprietors of the Tremont Mills," of which design the following is a specification.

My design consists of a locomotive-engine with smoke issuing from the smoke-stack, with steam issuing from the safety-valve, with the head and shoulders of a man seen through the forward open window of the cab, with the word "PROGRESS" on a panel just below the windows of said cab, with the figures "1870" on the upper part of the shield between the driving-wheels, with the letters "T M" on said shield below said figures, with the letters "T M" on the

steam-cylinder, with a penon or signal-flag floating from a perpendicular staff, which stands on the platform over the forward wheel of the truck-frame, and with an imp standing on said platform in front of and leaning against said staff. Said locomotive stands on a railroad-track. Said track rests on sleepers which lie on the ground. In front of the lantern of the locomotive, and over the cow-catcher, are two imps riding on an owl.

I claim as my invention—

The design for a trade-mark, as described and shown.

WILLIAM A. BURKE.
